UNITED STATES PATENT OFFICE

JUNIUS EDGAR TUCKER, OF MEMPHIS, TENNESSEE, ASSIGNOR OF ONE-HALF
TO WILLIAM S. BRIAN, OF MEMPHIS, TENNESSEE.

PAPER-SHEET-FEEDING MECHANISM FOR PRINTING-PRESSES.

No. 852,473.

Specification of Letters Patent.

Patented May 7, 1907.

Application filed December 14, 1905. Serial No. 291,747.

To all whom it may concern:

Be it known that I, JUNIUS EDGAR TUCKER, a resident of Memphis, in the county of Shelby and State of Tennessee, have invented certain new and useful Improvements in Paper-Sheet-Feeding Mechanism for Printing-Presses; and I do hereby declare the following to be a full, clear, and exact description of the invention, such as will enable others skilled in the art to which it appertains to make and use the same.

My invention relates to improved paper sheet feeding mechanism for printing presses, the object of the invention, being to provide simple and efficient means for feeding sheets singly from the top of a pile of sheets, and to provide means controlled by the sheet being fed, to accurately regulate the feed.

With this object in view, the invention consists in certain novel features of construction and combinations and arrangements of parts as hereinafter set forth and pointed out in the claims.

In the accompanying drawings; Figure 1 is a view in side elevation illustrating my improvements; Figs. 2 and 3 are enlarged views showing details of construction.

1 represents a pile of paper sheets having any suitable means for elevating the pile as sheets are removed from the top. The sheets are fed from the top of the pile between wheels or rollers 2, 3, to tapes 4 for conveying the sheets to the platen. At the ends of the shaft 2^a which carries the wheels or rollers 2, slotted crank-arms 5 are provided and to these crank-arms, the forward ends of rods 6 are movably connected. Stops 24 are provided, to limit the downward movement of the rear ends of said rods. Depending arms 7 are adjustably secured to the rods 6 by means of set screws 8 and at their lower ends, the arms 7 carry inclined feed scrapers 9 to move the sheets forward from the pile. The scrapers 9 are made of bone or other suitable material and are adjustably secured to the arms 7 by means of set screws 10.

A long bar 11 is fulcrumed near its forward end (as at 11^a) to a part of the framework (not shown) and projects at its rear portion, over a pin 12 projecting laterally from a disk 13, mounted eccentrically on a cross rod 7^a connecting the depending arms 7. The bar 11 is provided at its forward end with a depending hook, normally engaged by a trip

lever 16, the forward end of the rod 11 being so supported by the trip lever 16 that the weight of the rear, heavier portion of said rod will not be borne by the pin 12 on disk 13. The trip lever 16 is pivoted between its ends to an arm 17 projecting from a rock shaft 18, suitably mounted in the framework and the lower end of said trip lever projects across the path of the paper sheet as the latter moves from the pile to the feeding tapes. An arm 19 is secured to the shaft 18 and projects upwardly, in a diagonal direction therefrom, terminating at its upper end in position to be actuated by a cam 20 on the shaft 2^a. Guide fingers 21 are also secured to the shaft 18 and extend forwardly beyond the lower end of the trip lever 16. The forward ends of the fingers 21 are also in the path of the sheets as they move from the pile to the feed belts.

Below the eccentrically mounted disk 13, a fixed track 22 is located, but the disk is held out of contact with this track when the scrapers are in contact with the pile of paper, by means of a light spring 23, said spring acting to turn the disk on its eccentric mountings a sufficient distance for this purpose. When however, the weight of the rod 11 is permitted to come upon the pin 12 of disk 13, the power of the light spring 23 will be overcome, and the disk will be caused to engage the track and will be made to roll thereon by the forward movement of the rods 6 during the operation of the crank-shaft 2^a.

The operation of the mechanism is as follows:—The rotation of the shaft 2^a causes its cranks 5 to move the rod 6 forwardly from the position shown in the drawing and the scrapers to move the top sheet of paper forwardly. The forward edge of the sheet will engage the trip lever 16 and swing the latter until the end of the sheet strikes the fingers 21, at which time, the trip lever 16 will have released the hooked end of rod or bar 11. Just prior to the release of bar 11, the disk or eccentric was above and out of contact with the track 22, but at the instant the bar 11 is released, its heavier end, resting on the pin 12 of disk 13, will cause said disk to turn on its eccentric mounting, against the slight resistance of spring 23, and to engage track 22. As the crank continues to turn, the rod 6 will be moved forwardly and the disk or eccentric 13 caused to roll on the track 22. During this forward movement of the rod 6

and the rolling of the disk 13 on track 22, the eccentric connection of the disk with the arms 7 will rise and cause the arms 7 and scrapers 9 to be elevated out of contact with the paper sheet. The crank arms 5 will have then moved past their lowest half stroke and will begin to elevate the forward ends of the rods 6, the rear ends of said rods coming in contact with and resting upon the stops 24. 5 As the cranks 5 continue to rise, the forward ends of the rods 6 will be raised sufficiently to lift the disk or eccentric off of the track 22. The cam 20 will have moved arm 19 and turned shaft 18 to elevate the fingers 21, so 10 that the sheet can pass to the feeding tapes. As the eccentrically-mounted disk 13 rolls on the track 22 and the pin 12 thereon rises, the bar 11, resting on said pin, will be turned on its fulcrum and its hooked end will be moved 15 rearwardly. The movement of the shaft 18 by the cam 20 will now bring the trip lever 16 and the hooked end of bar 11 into locked engagement, thus relieving the pin 12 on disk 13, of the weight of said bar 11. The spring 20 23 can now cause the disk or eccentric to turn to the position shown in Fig. 2, with said disk or eccentric above the track and the fingers 9 in contact with the top sheet of the pile. During the continuance of operation of the 25 mechanisms, the movements above described will be repeated.

Various slight changes might be made without departing from the spirit of my invention or limiting its scope, and hence I do not wish to limit myself to the precise details herein set forth.

Having fully described my invention what I claim as new and desire to secure by Letters-Patent, is;

- 40 1. In a feeding mechanism for printing presses, the combination with a rod, means for moving said rod longitudinally and a scraper carried by said rod, of an eccentric actuated to raise the scraper by the longitudinal movement of the rod, means for retaining said eccentric inoperative during a portion of the movement of said rod, and means controlled by the sheet being fed, to move the eccentric in position to be actuated 45 by the rod through another part of the throw of the latter, to raise the scraper.
2. In feeding mechanism for printing presses, the combination with a rod, means for reciprocating said rod, and a depending scraper carried by said rod, of a disk having eccentric connection with said scraper below the rod, a fixed track between said disk and the lower end of the scraper, means for holding the disk out of contact with said track, 50 means for moving said disk into contact with the track, and means controlled by the sheet for releasing said last-mentioned means.
3. In feeding mechanism for printing presses, the combination with a rod, means 65

for reciprocating the same, a depending arm carried by said rod and a scraper at the lower end of said arm, of a disk having eccentric connection with said arm, a fixed track below said disk, means tending to retain the disk out of contact with the track, a pin on said disk, a pivoted rod projecting over said pin, and a trip device controlled by a sheet being fed, to release and permit its rear end to descend and move the disk into 75 contact with the fixed track during the movement of the first-mentioned rod.

4. In a feeding mechanism for printing presses, the combination with a shaft, a reciprocating rod actuated by said shaft, and a scraper carried by said rod, of a disk having eccentric connection with said scraper, a fixed track below said disk, means for holding said disk out of contact with the track, means actuated by the paper being fed, to move the disk into contact with the track, and means actuated by said shaft to restore the parts.

5. In a feeding mechanism for printing presses, the combination with a reciprocating bar and a scraper carried thereby to move a sheet of paper off the top of a pile, of means for elevating the scrapers from operative position, a trip actuated by the paper for controlling the operation of said elevating means 95 guard fingers serving to hold the sheet temporarily, a cam or eccentric and means actuated by said cam or eccentric and operating to move said guard fingers and restore the trip.

6. In a feeding mechanism for printing presses, the combination with a reciprocating bar or rod, an arm depending therefrom and a feed scraper at the lower ends of said arm to move a sheet of paper off the top of a pile, of a horizontal track; a cam carried by the depending arm and normally above the track, and means controlled by a moving sheet to permit the cam to engage the track, roll thereon and elevate the scrapers.

7. In a feeding mechanism for printing presses, the combination with a reciprocating rod, a crank shaft for reciprocating said rod, an arm depending from said rod and a feed scraper at the lower end of said arm to engage and move a sheet of paper off a pile, of a horizontal track, a cam carried by the arm, to run on said track to elevate the scraper from the top sheet, means normally holding the cam out of contact with the track and trip mechanism operated by a moving sheet to move the cam into engagement with the track to elevate the scraper.

In testimony whereof, I have signed this specification in the presence of two subscribing witnesses.

JUNIUS EDGAR TUCKER.
